CLAIM

The ornamental design for an aerosol sensor as shown and described.

DESCRIPTION

FIG. 1 is a perspective view of an aerosol sensor showing our new design, shown from the top, front, and right; FIG. 2 is another perspective view thereof, shown from the bottom, rear, and left;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines illustrate portions of the aerosol sensor that form no part of the claimed design.
